Examples of the compounds of the general Formula II

	X'		SO_2		X	X'

sample was scanned by use of a microdensitometer having an open aperture of 25μ .)

TABLE 1

Amount of compound (I) (g. per mole of AgX)	Amount of compound (II) (g. per mole of AgX)	Relative speed	Fog	RMS
[I]-4, 0.06 g.		100	0.14	85
[I]-4, 0.12 g.		96	0.10	83
	[III]-1, 1.4 g.	90	0.08	80
	[III]-1, 2.8 g.	103	0.08	83
[I]-4, 0.06 g.	[III]-1, 1.4 g.	100	0.08	83
[I]-4, 0.06 g.	[III]-1, 2.8 g.	99	0.08	61
[I]-9, 0.06 g.	[III]-1, 1.4 g.	89	0.06	58
[I]-13, 0.06 g.	[III]-1, 1.4 g.	101	0.08	65
[I]-18, 0.10 g.	[III]-1, 1.4 g.	98	0.08	70
[I]-4, 0.06 g.	[III]-2, 1.4 g.	102	0.06	62
[I]-4, 0.06 g.	[III]-2, 1.4 g.	93	0.07	64
[I]-4, 0.06 g.	[III]-3, 1.4 g.	104	0.08	58
[I]-4, 0.06 g.	[III]-7, 1.4 g.	100	0.08	60
[I]-4, 0.06 g.	[III]-8, 1.4 g.	100	0.08	63
[I]-4, 0.06 g.	[III]-10, 1.4 g.	98	0.06	58
[I]-4, 0.06 g.	[III]-12, 1.4 g.	96	0.06	54

Coupler (4):

9

Formalin and 300 ml. of 5% saponin per mole of AgX , and coated on a triacetate film base to a dry film thickness of 5μ , followed by drying, to prepare a photographic film. The photographic film was exposed through an optical wedge to a light of regulated amount, developed at 20° C . for 10 minutes by use of a color developer solution of the composition shown below, and then subjected to the same fixing and the like treatments as in Example 1.

Composition of color developing solution:

G.

Anhydrous sodium sulfite	2.0
4-amino-N,N-diethylaniline hydrochloride	5.0
Sodium carbonate (monohydrate)	50.0
Potassium bromide	1.0
Water to make 1,000 ml.	

Water to make 1,000 ml.

TABLE 3

Amount of compound (I) (g. per mole of AgX)	Amount of compound (II) (g. per mole of AgX)	Relative speed	Fog	RMS
[I]-9, 0.1 g.	-----	100	0.10	92
[I]-9, 0.1 g.	[II]-6, 3 g.	96	0.06	88
[I]-9, 0.1 g.	[II]-6, 3 g.	98	0.08	90
[I]-9, 0.1 g.	{[II]-6, 2 g. [II]-1, 1 g.}	96	0.08	64
[I]-9, 0.05 g.	{[II]-6, 3 g.}	95	0.06	68
[I]-2, 0.05 g.	{[II]-6, 3 g.}	98	0.06	66

From Table 3, it is understood that marked improvement in graininess can be attained also in the case of a combination of two kinds of the compound (I) and one kind of the compound (II) or a combination of one kind of the compound (I) and two kinds of the compound (II).

EXAMPLE 4

A high speed, light-sensitive silver iodobromide photographic emulsion (containing 4.5 mole percent of AgI, and 160 g. of gelatin per mole of AgX) was subjected to second ripening, and then incorporated with 1.4 g./mole AgX of 5-methyl-7-hydroxyl-1,3,4-triazaindolizine and each of the two solutions (1) and (2) of the compositions shown below to prepare two green-sensitive emulsions.

10

Composition of coupler dispersion:

Coupler (6)	g	82
2,5-di-(6-octylhydroquinone	g	3
Tricresyl phosphate	g	60
Ethyl acetate	g	250
5% alkanol B	ml	320
3% gelatin	ml	2,000

Subsequently, each of the above-mentioned emulsions was mixed with the thus prepared coupler dispersion, charged with 120 ml. of 1% Formalin and 500 ml. of 5% saponin per mole of AgX , and coated on a triacetate film base to a dry film thickness of 5μ , followed by drying to prepare samples. These samples were subjected to the same treatments as in Example 1 to obtain the results as shown in Table 4.

TABLE 4

	Relative speed	Fog	RMS
Solution:			
1-----	100	0.10	88
2-----	100	0.07	64

25 As seen in Table 4, the sample according to the present invention is markedly improved in graininess without any loss in speed.

What we claim is:

1. A color photographic material containing a silver halide light-sensitive coupler-containing emulsion layer, at least one compound of the formula

40 wherein R_1 , R_2 and R_3 are individually hydrogen, lower

	Solution	
	1, grams	2, grams
Sensitizing dye:		
	0.2	0.2
Compound (I)-5	0.06	
Compound (II)-4		2.00
Methyl alcohol	(i)	

1 300 milliliters.

On the other hand, a coupler of the structure shown below was dispersed by means of a high speed rotary mixer together with such components as set forth below to form a coupler dispersion of the composition shown below, in which the amount of each component is per mole of AgX .

Coupler (6):

alkyl, alkenyl, aryl or aralkyl, and at least one compound of the formula

wherein R_4 is hydrogen, lower alkyl, or aralkyl, and X and X' are individually hydrogen, alkyl, alkoxy or halogen.

2. The photographic material according to claim 1, wherein the compound of the Formula I and the compound of the Formula II individually are incorporated into two separate and adjacent layers of said material.

75 3. The photographic material according to claim 1,

11

wherein the compound of the Formula I and the compound of the Formula II are incorporated into the same layer of said material.

4. The photographic material according to claim 1, wherein the alkenyl group is

or
